UNITED STATES PATENT OFFICE

160,160

HANDLE FOR DENTAL INSTRUMENTS

Hugo Friedman, Chicago, Ill., assignor to Hu-
Friedy, Inc., Chicago, Ill., a corporation of
Illinois

Application May 20, 1949, Serial No. 2,776

Term of patent 14 years

(Cl. D24—1)

To all whom it may concern:

Be it known that I, Hugo Friedman, a citizen of the United States, residing at Chicago, in the county of Cook and State of Illinois, have invented a new, original, and ornamental Design for Handles for Dental Instruments, of which the following is a specification, reference being had to the accompanying drawing, forming a part thereof, in which

Fig. 1 is a perspective view of a handle for dental instruments, embodying my new design;

Fig. 2 is a side elevational view thereof;

Fig. 3 is a top plan view thereof;

Fig. 4 is a section substantially on the line 4—4 of Fig. 1; and

Fig. 5 is an end view of the handle from the right as viewed in Fig. 3.

I claim:

The ornamental design for a handle for dental instruments, substantially as shown.

HUGO FRIEDMAN.
